 McKenna Brass & Manufacturing Company,
 Inc., Pittsburgh, Pa., a corporation of Penn-
 sylvania

Application May 8, 1931, Serial No. 535,883

8 Claims. (Cl. 226—96)

This invention relates to filling machines, and particularly to a novel form of bearing and support for the rotatable portions thereof.

In many filling machines there is provided a base having a rotatable portion supported by a column on the base, which rotatable portion carries the filling heads and bottle holders for the bottles to be filled. The operation of the machine is such that considerable thrust is developed tending to shift the bottom of the rotatable machine portion out of alinement. This has heretofore been resisted by means of a bearing on the base near the bottom of the column and extending around the same. Such construction is open to numerous objections. It limits the size of the column which may be employed and this tends to produce a "springy" machine. In the event of wear, it is practically impossible to renew the bearing without shipping the machine back to the factory. Lubrication is difficult and therefore is frequently neglected, thus causing rapid wear.

I overcome this by forming a peripheral track around the rotatable portion of the machine and side thrust bearings engaging such track. The thrust is thus restricted much more effectively than with the old construction, and lubrication is materially simplified. Furthermore, it is possible to design the column in such manner as to provide ample strength.

I also make provision for positively centralizing the rotatable portion of the machine with respect to the column during the installation of side thrust bearings. For this purpose I prefer to employ the driving gear for the rotatable portion of the machine. I arrange centering means on the rotatable portion of the machine, over which means the gear is slidable. I also arrange a centering means on the column for engaging the gear. When the machine is completely assembled the gear is out of engagement with the last mentioned centering means, but it may be lowered so as to engage the same while still engaging the centering means on the rotatable part of the machine. In this manner the parts are accurately centered during installation or adjustment of the bearings.

In the accompanying drawings illustrating a present preferred embodiment of the invention,

Figure 1 is a perspective view of the machine partly broken away;

Figure 2 is a central vertical section;

Figure 3 is a horizontal section taken on the line III—III of Figure 2; and

Figure 4 is a section to enlarged scale showing one of the side thrust bearings.

The machine illustrated in the drawings comprises a base 2 having a column 3 upstanding therefrom. A table 4 surrounds the column 3. It has an upper flange 5 and a lower flange 6 between which extend guides 7 carrying bottle holders 8. The bottle holders are positioned below filling heads 9 on a bonnet 10. The bonnet 10 rotates about a post 11 forming an extension 10 of the column 3. The table is supported by a roller bearing 12 carried on the column 3.

In order to resist the thrusts which tend to rock the table during operation, I provide a peripheral track 13 on the lower portion of the table 4, and side thrust bearings 14 which engage such track. The side thrust bearings 14 are carried on brackets 15 and 16 secured to the base 2 by screws 17.

Figure 4 illustrates one of the brackets 15 in section. It is bored to receive a post 18 having a shoulder 19 engaging the upper face of the bracket 15 and a nut 20 threaded on the lower end of the post 18 which holds the post firmly in place. A roller 21 is carried on the upper portion of the post and is held in place by a retaining cap 22 and screw 23. The post is drilled at 24 so that lubricant may be supplied at 25 to the roller 21.

The rotatable portion of the machine comprising the table 4, the bonnet 10 and associated mechanism is driven by a ring gear 26 secured to the bottom of the table by screws 27. The ring gear 26 meshes with an intermediate gear 28 which, in turn, meshes with a pinion 29. The pinion 29 is driven by worm gearing 30 through a variable speed transmission within the housing 31 from a motor contained in such housing. In Figure 1 I have shown the adjusting wheel 32 for the variable speed transmission and a hand wheel 33 on the shaft of the motor.

In assembling or adjusting the machine it is necessary that the table be exactly centralized during the fitting of the brackets 15 and 16 carrying the bearings 14. To insure this I provide an annular step 34 on the column 3, which step is of just the right diameter to engage the inner face 35 of the ring gear 26. If the screws 27 are backed off so as to lower the gear 26, it engages the step 34 and centralizes the table with the column. It will be noted that the gear has an annular face 36 engaging the outer face 37 of a flange formed on the bottom of the table 4. The parts are so proportioned that the step 34 engages the face 35 before the annular face 36 is out of engagement with the face 37. When the parts

are in such position the brackets may be bolted in the proper position. In the event of wear, the brackets may be re-located or new rollers 14 may be installed. Either operation may be carried out with but little difficulty and without re-turning the machine to the shop.

I have illustrated and described the present preferred embodiment of the invention. It will be understood, however, that it is not limited to the form shown but may be otherwise embodied within the scope of the following claims.

I claim:

1. A filling machine comprising a base having a column, a table extending down over the column and also having a portion extending outwardly therefrom, a track formed on the outwardly extending portion, a bearing adjacent the top of the column for supporting the weight of the table, side thrust bearings engaging the track, and means for holding the outwardly extending portion centralized during fitting of the side thrust bearings.

2. A filling machine comprising a base, a table having upper and lower radially extending portions, guides extending between such portions, bottle holders on the guides, a bearing adjacent the plane of the upper table portion for carrying the weight of the table, a track formed on the lower table portion, and side thrust bearings engaging the track.

3. A filling machine comprising a base, a table rotatably mounted thereon, a peripheral track around the table, side thrust bearings engaging the track, a ring slidable in an axial direction and relative to the base of the table, centering means on the base for maintaining the axis of the ring concentric with the axis of the base during such sliding, and centering means on the table for maintaining the axis of the ring concentric with the axis of the table during such sliding, the two centering means being relatively so positioned that they may be simultaneously engaged by the ring, whereby the table may be accurately positioned during fitting of the bearings.

4. A filling machine comprising a base, a table rotatably mounted thereon, a peripheral track around the table, side thrust bearings engaging the track, a ring gear secured to the table and effective for driving the same, the ring gear being slidable in an axial direction, means for holding it centralized during such axial movement, and centering means on the base for engaging the ring gear when it is out of its normal position, the centering means being so positioned that it engages the gear while the same is still held cen-

tralized, whereby the table may be accurately positioned during fitting of the bearings.

5. A filling machine comprising a base, a table rotatable thereon, an annular series of bottle supports on the table and bottle filling means for cooperating with the bottles in the supports during a portion only of the rotation of the table, and means for supporting the table and bracing it against the unbalanced forces of the filling operation, comprising a bearing carried by the base and supporting the weight of the table, a peripheral track around the table at an elevation different from that of the bearing, and a plurality of side thrust bearings engaging the track.

6. In a filling machine, a base having an up-standing portion, a column extending upwardly through said up-standing portion, a table concentrically arranged around the column, a bearing on the up-standing portion, said table extending radially over the up-standing portion and supported by said bearing, a peripheral track around the table at an elevation different from that of the said bearing, and a plurality of side thrust bearings on the base engaging the track.

7. In a filling machine, a base, a column extending upwardly from the base, a table having upper and lower radially extending portions concentrically arranged around the column, said table having thereon a series of bottle supports, bottle filling means for cooperating with bottles on the supports during a portion of the rotation of the table, a bearing between the base and one of the radially extending portions of the table for supporting the table, the other radially extending portion of the table being coaxially arranged with a cooperating portion of the base, one of said coaxially arranged portions constituting a track and side thrust bearings carried by the other of said coaxial portions for engaging said track, the track being at an elevation different from that of the bearing on the base.

8. In a filling machine, a base having an up-standing portion, a column extending upwardly through said up-standing portion and concentrical therewith, a table concentrically arranged around the column, said table having upper and lower radially extending portions, and a series of bottle supports, a bearing on said up-standing portion of the base adjacent the plane of the upper table portion for carrying the weight of the table, a track formed on the lower table portion, and side thrust bearings on the base for engaging the track.

LOUIS DE MARKUS.
